UNITED STATES PATENT OFFICE.

ALEXANDER PINKNEY SMITH, OF MACON, GEORGIA.

BASKET.

Application filed March 24, 1926. Serial No. 97,087.

My invention relates to improvements in fasteners, particularly adapted for securing the covers of fruit baskets and the like in position.

- 5 It is an object of the invention to provide a fastener which may be easily applied to securely hold the cover of the basket in place without injury to its contents, or liability of displacement while in transit.
- 10 A further object of the invention is to provide a reinforcing member carried by the cover adapted to be engaged by the fastener whereby the cover structure is relieved from undue strain and which enables the cover to be more firmly secured in place.

A further object of the invention is to provide a fastener which when not in use is movable so as not to interfere with the nesting of the baskets and may be employed as 20 a retaining means for holding the baskets in nested relation.

Another object of the invention is to provide a fastener of the above-mentioned character which is simple and durable in 25 construction, reliable and efficient in use and inexpensive to manufacture.

Other objects and advantages of the invention will be apparent during the course of the following description.

30 In the accompanying drawing, forming a part of this specification and in which like numerals are employed to designate like parts throughout the same,

Fig. 1, is a top plan view of a basket, 35 showing my fastener applied thereto,

Fig. 2, is a fragmentary side elevation of the same,

Fig. 3, is a perspective view of the reinforcing member employed in conjunction 40 with my fastener,

Fig. 4, is a detail cross sectional view showing how the fastener is applied,

Fig. 5, is a top plan view showing a modified form of the invention,

45 Fig. 6, is a fragmentary side elevation of the same,

Fig. 7, is a view showing the position of the fastener when a series of baskets are in nested relation, and,

50 Fig. 8, is an enlarged sectional view taken on lines 8—8 of Fig. 7.

In the drawing, wherein for the purpose of illustration I have shown a preferred embodiment of my invention, a conventional

55 type of basket cover is shown in Figs. 1 and 2, having the usual cross slats 3, 4, 5, 6, 7 and

8, the slats 3 and 4 being paired and disposed in spaced parallel relation to each other, as are also the slats 5 and 6 and the slats 7 and 8. The outer ends of the slats are secured 60 to the upper edge of the band or ring 13, as indicated at 14. A retaining slat 9 extends across the top of the cover having its ends inserted in the usual loops or handles 15 of the basket.

Arranged at diametrically opposite points of the cover are re-inforcing members 16, formed from a piece of wire which extends across the ends of the slats 5 and 6, having its ends bent downwardly at right angles 70 and terminating in upturned hooks 17 engageable with the lower edge of the band 13.

The fasteners 18, as more clearly shown in Fig. 4, consist of a piece of pliable wire having one end bent at right angles, as at 20 and pivotally mounted in the inner and outer hoops 11 and 10 of the basket, extending through the staves 12 which are clamped between the hoops 11 and 10. When not in use the fasteners 18 normally lie in a horizontal plane in contact with the outer surface of the hoop 10, as shown in dotted lines in Fig. 2. To secure the cover in place the fasteners are rotated to a vertical position and their upper ends 19 are bent over the re-inforcing members 16, which are bowed slightly outward. It will be seen that the cover is positioned so the fasteners will engage the re-inforcing members intermediate the slats 5 and 6, and the bent end extends down far enough to prevent circumferential movement of the cover.

As shown in Figs. 7 and 8, the fasteners may be employed to retain the baskets in nested relation when moved from place to place, by turning the fasteners down and bending the lower ends, as at 28, into frictional engagement with the outer band 10 of the next basket below.

A modified form of the invention is shown in Figs. 5 and 6, consisting of a continuous wire hoop 25, substituted for the band 13, which bears on the ends of the cross slats and extends beneath the ends of the retaining slat 9, externally of the handle. When this construction is used the fasteners 18 are bent over the hoop 25, as well as the re-inforcing members 16.

Thus, it is seen that a simple and efficient fastener is provided to secure the covers of baskets in place, which will firmly secure

the cover against displacement while in transit.

It is to be understood that the form of my invention herewith shown and described is to be taken as a preferred example of the same and that certain changes in the shape, size and arrangement of the parts may be resorted to without departing from the spirit of the invention or the scope of the subjoined claims.

Having thus described my invention, I claim:

1. A basket fastener, in combination with the usual basket cover, of a re-inforcing member extending across a pair of slats of the cover and attached thereto and a fastener mounted in the rim of the basket, the free end of said fastener being adapted to engage said re-inforcing member intermediate said slats.

2. A basket cover fastener consisting of a piece of pliable wire having one end

mounted in the rim of the basket, and a re-inforcing member extending across a pair of slats of the cover having its ends bent downwardly and terminating in upturned hooks engaging the lower edge of the cover band, the free end of said fastener being bendable over said re-inforcing member.

3. A basket cover fastener consisting of a piece of pliable wire having one end mounted in the rim of the basket and a re-inforcing member attached to the cover having a horizontal portion in close relation to the cover band, said horizontal portion having its ends bent downwardly and terminating in upturned hooks engaging the lower edge of the cover band, the free end of said fastener being adapted to engage the horizontal portion of said re-inforcing member.

In testimony whereof I affix my signature.

ALEXANDER PINKNEY SMITH.
